UNITED STATES PATENT OFFICE

2,191,933

ROOFING

Joseph Dubreuil, Taschereau, Quebec, Canada

Application February 10, 1939, Serial No. 255,689

1 Claim. (Cl. 108—12)

The present invention relates to improvements in roofing.

An object of the invention is the provision of roofing of generally improved design.

5 Another object of the invention is the provision of roofing constructed so as to allow contraction and expansion of the roofing parts.

A further object of the invention is the provision of roofing of the above character designed 10 to efficiently shed water therefrom.

Still another object of the invention is the provision of roofing of the aforesaid character which is durable in construction and which can be conveniently assembled.

15 A still further object of the invention is the provision of roofing of the above character which is relatively simple and inexpensive in construction.

Other objects and advantages of the invention 20 will become apparent as the description progresses.

In the accompanying drawing forming a part 25 of this specification and in which like reference characters are employed to designate corresponding parts throughout the same:

Figure 1 is a transverse section through a gable form of roof with the improved roofing thereon,

Figure 2 is a similar view showing a gable roof with a lean-to structure at the side,

30 Figure 3 is an enlarged section taken on the line 3—3 of Figure 1, and

Figure 4 is a fragmentary plan of the assembled roofing viewed from line 4—4 of Figure 1.

Referring to the drawing, wherein for the 35 purpose of illustration is shown a preferred embodiment of the invention, F generally designates a roofing frame embodying king-posts 10 supported on tie beams 11 and including sloping rafters 12 supporting longitudinally extending purlins 13.

40 The improved roofing assembled on the framework essentially embodies elongated covering strips 15 and joined strips or battens 16 usually assembled in transversely extending positions, as shown at Figures 1 and 2.

The main covering strips 15 which may be 45 formed of wood or other suitable material are shaped, in cross sectional contour, to provide a flat bottom face 18 supported on the purlins and 50 having the top or outer face shaped to provide a longitudinally extending centrally arranged concave channel 19 extending over the major width of the strip. At each side of the channel 19 the top face of the strip is provided with flat margins 20. At one side edge the strip is formed

5 with a relatively narrow outwardly protruding ridge 21 having a rounded curvature at the inner side, while the opposite side edge is formed with a somewhat wider ridge 22 rounded at the inner side and beveled at its outer side.

The elongated joining strips or battens 16 are shaped, in cross section, so that the top or outer surface slopes downwardly inside, as indicated 10 at 24, from a center ridge, while the inner surface is shaped to provide a beveled triangular shaped 15 longitudinally extending ridge 25, slightly off the transverse centre providing a comparatively narrow groove 26 and a wider groove 27. Thus, the inner surface is provided at each side margin with the ridge 28 rounded at the inner edge, as 20 shown to advantage at Figure 3.

During assembly, the main roofing strips 15 are laid in parallel position spaced from one another and one side portion is securely fastened to the roof frame as by nails 30 driven transversely through the wider ridge portion 22. The 25 battens 16 are thereafter positioned upon adjacent side portions of the covering strips, the narrower groove 26 in the underside thereof being shaped to fit snugly on the wider ridge 22 of 30 the strip, while the wider groove of the batten accommodates therein the narrower ridge portion 21 of the covering strip, as clearly illustrated at Figure 3. A nail, or other suitable fastening means 31, driven through the centre of each 35 batten 16 into the framework serves to firmly secure the batten in position. As will be noted from the drawing, the ridges and grooves on the battens and covering strips are designed so that the outer face of the batten ridges will fit against 40 the flat margins 20 of the cover strips to provide a firm joint effectively covering the spacing grooves between the cover strips and at the same time allowing for transverse contraction and expansion of the cover strips relative to the 45 battens.

The sloping top surfaces of the battens and the concave grooves in the cover strips are designed to effectively drain the water from the 50 roofing by directing the same into the draining channels.

This construction provides relatively simple and efficient roofing which affords a long lasting roof covering effectively protected against leakage and injury due to the accumulation and 55 freezing of water thereon.

It is to be understood that the form of my invention herein shown and described is to be taken as a preferred example of the same and that various changes as to the shape, size and 55

arrangement of parts may be resorted to without departing from the spirit of the invention or the scope of the subjoined claim.

Having thus described my invention, I claim:

- 5 In roofing of the character described, a plurality of spaced covering strips having their outer surface shaped to form a centrally disposed longitudinally extending channel and upstanding ridges at the side margins, a plurality of recessed

batten strips fitted over the adjacent ridges of each pair of covering strips to cover the space there-between and to overlap the adjacent ridges of covering strips, means for securing one side of each covering strip in fixed position, and means extending through the battens and between adjacent covering strips for immovably securing the batten strips in position.

JOSEPH DUBREUIL.
